UNITED STATES PATENT OFFICE.

ALLEN B. CLARK AND JOEL J. CLARK, OF CANISTEO, NEW YORK.

NECK-YOKE.

SPECIFICATION forming part of Letters Patent No. 227,413, dated May 11, 1880.

Application filed October 24, 1879.

To all whom it may concern:

Be it known that we, ALLEN B. CLARK and JOEL J. CLARK, of Canisteo, in the county of Steuben, State of New York, have invented a new and useful Improvement in Neck-Yokes, which improvement is fully set forth in the following specification, reference being had to the accompanying drawings.

Our invention relates to an improvement in neck-yokes; and it consists in an outer tube having two longitudinal slots cut through its side and a thimble to fit in each end of the tube, which thimbles are connected together by a spiral spring and provided with set-screws, so that after one or both of the thimbles have been partially drawn out they can be locked in any desired position, as will be more fully described hereinafter.

Figure 1 is a perspective of a neck-yoke embodying our invention. Fig. 2 is a vertical longitudinal section of the same.

a represents the neck-yoke, which is formed from a metal tube and provided with a longitudinal slot, c, on each side of its center. Into the open ends of this hollow yoke are inserted the two extensible tubes d, which are closed at their outer ends and provided with the eyes e to receive the rings g. The inner ends of

these tubes d are open, so as to receive the ends of the spiral spring i, which is placed in 30 between them. This spring serves to secure the two thimbles or tubes d together and to draw them back into the yoke after either one or both have been drawn out.

Passing through the slots into the thimbles 35 are the set-screws o, which serve to lock the thimbles in any one place, and thus keep the yoke always of the same length. When these screws are left loose the thimbles play freely back and forth, and thus allow the horses to 40 move outward to avoid mud-puddles, stones, or other obstructions that may be in the way.

Having thus described our invention, we claim—

In a neck-yoke, the combination of a tube, 45 a, provided with the two slots c, with the two thimbles d, spring i, and set-screws o, whereby the thimbles may either play freely in and out of the tube a, or the length of the yoke be kept always the same, substantially as shown.

ALLEN B. CLARK.
JOEL J. CLARK.
